UNITED STATES PATENT OFFICE

91,024

DESIGN FOR A HOUSING FOR A LOTION AND THE LIKE DISPENSING MACHINE

Eugene E. Frary, Los Angeles, Calif., assignor to
Utility Coin Machine Co., Los Angeles, Calif.

Application August 7, 1933. Serial No. 48,946

Term of patent 7 years

To all whom it may concern:

Be it known that I, EUGENE E. FRARY, a citizen of the United States, residing at Los Angeles, in the county of Los Angeles and State of California, have invented a new, original, and ornamental Design for a Housing for a Lotion and the like Dispensing Machine, of which the following is a specification, reference being had to the accompanying drawing, forming part thereof.

Fig. 1 is a front elevation of a housing, showing the new design.

Fig. 2 is a side elevation of the housing, showing the same design.

I claim:

The ornamental design for a housing for a lotion and the like dispensing machine, as shown.

EUGENE E. FRARY.
